UNITED STATES PATENT OFFICE.

WILLIAM REYNOLDS, OF NEW YORK, N. Y.

VIBRATION-ELIMINATOR.

1,088,035.

Specification of Letters Patent.

Patented Feb. 24, 1914.

Application filed June 2, 1913. Serial No. 771,226.

To all whom it may concern:

Be it known that I, WILLIAM REYNOLDS, a citizen of the United States, residing at New York, in the county and State of New York, have invented certain new and useful Improvements in Vibration-Eliminators, of which the following is a specification, reference being had to the accompanying drawings, forming a part thereof.

10 My invention relates to vibration eliminators in that class of pneumatic shock absorbers which forms the subject matter of my co-pending application, #725,134 filed October 11, 1912, and constitutes an improvement of the invention disclosed in that application.

Under certain conditions especially where a cushion of some material rigidity is interposed between members extending from 20 the running gear and body of a vehicle it is found that some of the members when subjected to severe shocks move away from the cushion; so that on the rebound there is some relative movement between the running gear and body which is not under all 25 of the resistance of the cushion and it is the primary object of my invention to oppose continuously all movement in either direction and however minute by the ever present 30 resistance of a cushion of that character which will not set up independent vibrations of its own. One means by which I attain this primary object is by distorting the cushion from its natural shape and when in 35 a distorted condition and under tension dispose the same between the body and running gear of the vehicle so that any relative movement between the body and running gear will be continuously resisted by 40 the cushion. The tendency of the cushion is to restore itself to its natural shape and the parts of the same in moving into their natural position have no tendency to go beyond this position, and for this reason I 45 place the cushion under an initial distortion so that it will be forced beyond its natural shape but all action will take place when the cushion is in distorted condition.

The various particular objects of the invention will be more fully set forth in the following description of one form of vibration eliminators embodying my invention, which consists in the new and novel features of construction and combinations of parts 55 hereinafter set forth and claimed.

In the accompanying drawings: Figure 1 is a longitudinal view through the rear axle of a vehicle looking toward one of the wheels and showing a preferred form of my invention mounted in place. Fig. 2 is a rear 60 elevation of the device shown in Fig. 1 and, Fig. 3 is a longitudinal vertical sectional view taken through the cushion shown in Figs. 1 and 2 and taken on the line 3-3 of Fig. 1: 65

Describing the embodiment illustrated the body 1 of the vehicle is resiliently supported from the running gear 2 by a suitable suspension such as the spring 3 and as the invention is adapted to be applied to the usual 70 form of vehicle, this running gear may include either the rear or driving axle as shown in Fig. 2, with obvious mechanical adaptations may include the front or steering axle, or the wheel shown may be mounted 75 on the usual steering spindle.

Interposed in any suitable position to be acted upon by the relative movement of body and running gear is a hollow cushion 4, which in this disclosure is shown to be a 80 rounded end cylinder preferably having slightly flattened sides, which is filled with compressible fluid such as air.

Extending from the body 1 is a bracket 6 having vertically spaced ledges 7 and 8, 85 the ledges 7 being spaced apart horizontally and the ledge 8 being disposed in a line therebetween. Affixed to the axle or other portion of the running gear is a similar bracket 9 having horizontally spaced ledges 90 10 in vertical alinement opposite the ledges 7 and an intermediate ledge 11 disposed between the ledges 7 and opposite the ledge 8.

With the normal load of the vehicle the ledges 7 and 10 are so spaced apart that the cushion 4 fits therebetween, preferably under slight compression, but the ledges 8 and 11 are positioned, in this disclosure, a distance apart less than the normal depth of the cushion 4 at this place. This disposition of 95 ledges provides a means for retaining the cushion in place even though a puncture or other accident, cause the same to become collapsed.

At present the cushion is inserted in place 105 between the ledges 7 and 11 and the ledges 10 and 8 before the cushion is blown up and then air is pumped into the same until the desired tension and distortion is obtained. This tension will act on the ledges 8 and 11 110

tending to separate them which will have the effect of lowering the body toward the running gear thus placing the spring 3 under tension which will have the effect of steady- 5 ing the body of the vehicle which is very de- sirable when riding with a light or no load.

- The most objectionable shock on a vehicle body is from the recoil which is upward and to provide a greater check to this movement 10 than is necessary to the movement in the opposite direction the ledges which check this upward shock are of materially greater cushion engaging area than the ledges which oppose the shock in the opposite direction. 15 Another advantage of this relatively broad engagement is that it tends to prevent the spring 3 from losing its tension when one of the pairs of wheels is shot by the action of the spring into a depression in the road as 20 this broad bearing engages a material area of the cushion to support the running gear relative to the body.

In operation any movement of the running gear to or from the body will cause 25 either the ledges 7 to approach the relative stationary ledges 10, compressing the cushion therebetween and permitting the ledge 8 to approach the plane of the ledges 10, or this movement will cause the ledges 10 30 to move toward the relatively stationary ledges 7 permitting the ledge 11 to approach the plane of the ledges 7, or both of these actions will take place simultaneously. It will be noted however that the ledges 8 and 35 11 are continuously in engagement with the cushion due to the fact that the cushion is always distorted at this place from its natural position, and this distortion is greater than any possible recovering movement be- 40 tween running gear and body.

By means of this construction I believe that I am the first to eliminate vibrations in a vehicle and to roll over irregularities in the road rather than bounce over them and 45 my invention is broadly drawn to this improvement.

While one form of the invention has been illustrated and described it is obvious that various other modifications within the skill 50 of the mechanic may be made in the construction herein shown and described without departing from the spirit of the invention, provided the means set forth in the following claims be employed.

Having thus described my invention, I 55 claim:—

1. In combination with members carried by the running gear and body of a vehicle, of a pneumatic cushion distorted from its normal shape, disposed between said members and continuously in engagement therewith, said members continuously positioned apart a distance less than the normal depth of the portion of the cushion between said members whereby any relative movement 60 65 between the running gear and vehicle will be opposed by said cushion while in distorted condition.

2. In combination with the body and running gear of a vehicle and a resilient suspension for the same, of a cushion disposed between said body and running gear continuously opposing all relative movement between said body and running gear, said cushion being under a tension and continuously acting on said resilient suspension to 70 75 maintain the same under tension.

3. In combination with the body and running gear of a vehicle, a pneumatic cushion, members fixed to the body and running gear 80 engaging the top and bottom of said cushion, to oppose movement of the running gear to and from said body, the member opposing the movement away from said body having a greater cushion engaging area than the 85 cushion engaging area of the members opposing motion in the opposite direction.

4. In combination with members carried by the running gear and body of a vehicle, said members having a limited movement 90 toward and from each other, of a cushion disposed between said members and continuously in engagement therewith, the portion of the cushion between said members being initially compressed a distance greater than 95 the maximum travel of the members relative to each other and held in distorted condition by said members, whereby any relative movement between the running gear and body of the vehicle will be continuously opposed by a 100 cushion distorted from its normal configuration.

In witness whereof I have hereunto set my hand in the presence of two witnesses.

WILLIAM REYNOLDS.
